Fig. 3

Fig. 4

Fig. 1 is a right front perspective view of the cooking range embodying my new design;

Fig. 2 is a side elevational view thereof;

Fig. 3 is a perspective view similar to Fig. 1 but showing the lower sliding portion of the range in its forwardly extended condition; and

Fig. 4 is a like perspective view with the hinged outer section of the sliding lower portion in dropped position.

The other side of the range not shown is like the side illustrated in the drawings.

I claim:

The ornamental design for a cooking range, as shown and described.
